UNITED STATES PATENT OFFICE.

CHARLES A. KRAUS, OF NEWTON HIGHLANDS, AND ROY D. MAILEY, OF LYNN, MASSACHUSETTS, ASSIGNORS TO ARTHUR A. NOYES, TRUSTEE, OF BOSTON, MASSACHUSETTS.

VAPOR ELECTRIC APPARATUS.

1,185,685.

Specification of Letters Patent. Patented June 6, 1916.

Application filed June 30, 1910. Serial No. 569,694.

To all whom it may concern:

Be it known that we, CHARLES A. KRAUS and Roy D. MAILEY, both citizens of the United States, and residents, respectively, of Newton Highlands and Lynn, in the counties of Middlesex and Essex and State of Massachusetts, have invented new and useful Improvements in Vapor Electric Apparatus, of which the following is a specification.

Our invention relates to the construction of vapor electric apparatus characterized by the employment of a metal container and consists of new and useful modes of containing and insulating the mercury cathode which is peculiar to such apparatus.

A typical example of vapor electric apparatus to which our invention is applicable is the mercury arc rectifier.

The advantages to be derived from the use of a metal container, provided other essentials of construction could be conserved, have been recognized for some time, but so far as we are informed the structure and essentials to complete efficiency in a metal contained rectifier have not been so far developed as to enable metal contained rectifiers to be operated on a practical commercial scale. Among the essential structural features there is required for such an apparatus some mode of holding and insulating the mercury cathode which shall protect it against accidental short circuiting and particularly against the undesirable consequences which follow on the deposition of metallic coatings upon surfaces adjacent to the mercury cathode. It has been suggested to coat the internal lower portion of a metal container with enamel for the purposes indicated, but while an enamel lining may be found effective within restricted limits of operation, enamels do not possess as high an insulating power as is desirable or indeed essential in connection with rectification of current at high potential; enamel coatings being in their nature more or less porous and thus presenting inherent defects.

To secure the desirable high degree of insulation, we prepare a cup constructed of material which, by reason of its composition and method of manufacture, is known to be free from pores or other imperfections. For this purpose, vessels or cups of porcelain, glass or fused quartz may be employed.

The mercury cathode cup is made of such size and proportions that it will fit into the bottom of the metal container where it may be secured by suitable means such as clips or supports welded to the interior of the metal container, by cementing to the container or by the fusion between the cup and the container wall of a low melting vitreous material. In such manner the insulation of the mercury cathode may be secured so far as concerns the passage of currents through the body of the insulating cup. But we have found it necessary in many cases to provide further for insulation with respect to the passage of electric currents from the insulating cathode cup.

It is well known that the anodes of a vapor electric apparatus, such as a rectifier container, deposit their material in the course of normal operation, and that this finely divided metallic material is deposited on the inner surfaces and adheres thereto with great tenacity. As the use of the vapor electric apparatus is prolonged, this coating of metallic substances becomes heavier and more continuous until finally the insulating power of the surfaces on which the metal is deposited becomes impaired, and this phenomenon is commonly known as "spattering"; in the ordinary rectifiers in which the containers are constructed entirely of insulating material, such as glass, the spattering from the anode is of little consequence. In the case of metal contained rectifiers, however, this factor assumes importance, and this is especially true of rectifiers in which, as we recommend, the anode is placed in close proximity to the mercury cathode so that the inner surface of the cathode containing vessel adjacent to and surrounding the anode is exposed to "spattering."

In order to preserve the superficial qualities of the cathode containing cup, in spite of metallic deposits by spattering, we make the walls of the cup reentrant, or in other words, provide the cathode cup with a curtain or screen between which and the outer walls of the cup there is an annular space so that a considerable zone of the cup surface is protected; deposits of metal being intercepted by the curtain or apron. Thus the outer surfaces of the apron and the inner surface of the outer cup will always be maintained in high insulating condition. The

curtain will not necessarily be integral with the walls of the cup, but we find it preferable to make it continuous with the walls of the cup since in that way the extent of insulating surface is substantially increased.

In the drawings hereto annexed, there is shown in vertical section a metal contained rectifier provided with cathode insulating devices which embody the present invention.

10 In this drawing A represents the metal container of the rectifier, B the main anode, C the auxiliary anode, D the mercury cathode, and B', C', D', represent the leads for the anodes and cathodes respectively, the 15 said leads being attached to and insulated from the container by means of the joints B², C², D². The lead D' is incased in a refractory insulating coating or sleeve, D³, which guards against undesirable arcing or 20 short-circuiting. Such an insulating covering, if properly compounded, may be adhesively attached to the lead, as by fusion; a vitreous composition, composed of about 60% soda glass, 28% borax, and 12% ferric 25 oxid, will be found suitable for this purpose. This sleeve or coating D³ covers substantially the whole of the lead D' inside the container, and extends below the surface of the mercury cathode. The mercury cathode 30 D is contained in the cup E which, for introduction into the container A, may be secured as by a holding ring F. As shown in the illustration, the outer wall of the cup E is joined to and preferably integral with 35 the reentrant depending curtain or apron H; the inner surface I of which is in a position to receive and entirely intercept the metallic particles spattered from the anodes B and C, the outer surface J of the curtain 40 being spaced from the inner surface K of the cup so that the inner extent of these two last mentioned surfaces is protected against metal spattering and constitutes an insulating surface of which the protective 45 character is permanently preserved. Where the curtain or apron H is continuous with the cup as shown in the drawings, the level of the mercury in the cathode D should be kept below the lower edge of the apron H.

50 The method of securing a cathode cup of the character above described in its position in the bottom of the metal container is a practical detail of some importance and we prefer to unite the cathode cup with the 55 metal container by fusing a low melting vitreous flux between the cathode cup and the container walls; such a lining should be continuous over the sides and bottom of the cup in order to avoid lead stresses due to 60 expansion and contraction. A suitable flux of vitreous material for this purpose is composed of borax with soda glass and preferably also the oxid of a magnetic metal such as iron. The composition of such vitreous 65 material forms the subject matter of an ap-

plication for patent Serial No. 514,858 filed on or about the 27th day of August, 1909.

What we claim and desire to secure by Letters Patent is:

1. In a vapor electric apparatus, a closed metal container, and a cup of insulating material in the bottom of the container to hold the mercury cathode, a cathode lead extending upward from the mercury cathode through the container walls secured to and insulated therefrom by a hermetic insulating seal. 70

2. In a vapor electric apparatus, a closed metal container, anodes suspended therein, a mercury cathode and a cup to contain the latter composed of insulating material 80 lodged in the bottom of the container.

3. In a vapor electric apparatus, a closed metal container, anodes suspended therein, a mercury cathode and a cup to contain the latter composed of insulating material 85 lodged in the bottom of the container and secured thereto by fused vitreous material.

4. In a vapor electric apparatus, a closed metal container, anodes suspended therein, a mercury cathode and a cup to contain the latter composed of insulating material 90 lodged in the bottom of the container, and a protective curtain to screen the cup against anode spattering. 95

5. In a vapor electric apparatus, a closed metal container, anodes suspended within the container, a mercury cathode, a cathode cup in the bottom of the container composed of insulating material, and a curtain of similar material interposed between the side walls of the cathode cup and the anodes and spaced from the side walls of said cup. 100

6. A vapor converter comprising a conducting casing, and a vaporizable electrode 105 within and insulated from the casing.

7. A vapor converter comprising a conducting casing having a cover, a vaporizable electrode within and insulated from the casing, a conductor supported by the cover 110 and extending into the vaporizable electrode, and an insulating sheath for said conductor.

8. A vapor converter comprising a conducting casing, a vaporizable electrode within and insulated from the casing, a conductor projecting from one side of the casing into the vaporizable electrode at the opposite side thereof, and an insulating sheath 115 for said conductor.

9. A vapor converter comprising a conducting casing, a vaporizable electrode within and insulated from the casing, a conductor projecting from one side of the casing into the vaporizable electrode at the opposite side thereof, and an insulating sheath for 120 said conductor also projecting into the vaporizable electrode. 125

10. A vapor converter comprising a conducting casing, a vaporizable electrode within and insulated from the casing, a con- 130

ductor projecting from one side of the casing into the vaporizable electrode at the opposite side thereof, and an insulator surrounding the conductor and separating it from the casing and also extending into the vaporizable electrode.

11. A vapor converter comprising a conducting casing, a vaporizable electrode within and insulated from the casing, a conductor projecting from one side of the casing into the vaporizable electrode at the opposite side thereof, and an insulator surrounding the conductor and separating it from the casing.

12. A vapor converter comprising a conducting casing, and an insulating vessel located within the casing and containing a vaporizable electrode.

13. A vapor converter comprising a conducting casing, and an insulating vessel located within the casing and containing a vaporizable electrode, a conductor projecting from one side of the casing into the vaporizable electrode at the opposite side thereof, and an insulating sheath for the conductor.

14. A vapor converter comprising a conducting casing, and an insulating vessel located within the casing and containing a

vaporizable electrode, a conductor projecting from one side of the casing into the vaporizable electrode at the opposite side thereof, and an insulating sheath for the conductor also projecting into the vaporizable electrode.

15. A vapor converter comprising a conducting casing, and an insulating vessel located within the casing and containing a vaporizable electrode and having its upper edge turned inwardly to shield the walls of the vessel from particles given off from the anode.

16. A vapor converter comprising a conducting casing, and an insulating vessel located within the casing and containing a vaporizable electrode, a conductor projecting from one side of the casing into the vaporizable electrode at the opposite side thereof, and an insulator surrounding the conductor and separating it from the casing.

Signed by us at Boston, Massachusetts, this twentieth day of June, 1910.
